TEMPERATURE CONTROLLED ALARM

Harold B. Miller and Axel T. Anderson,
Minneapolis, Minn.

Application May 27, 1940, Serial No. 337,522

16 Claims. (Cl. 116—102)

This invention has relation to a temperature controlled alarm.

An object of the invention is to provide a spring wound temperature controlled alarm of novel and improved construction.

A further object is to provide a temperature controlled alarm wherein will be incorporated various features and characteristics of construction novel both as individual entities of the alarm and in combination with each other.

A further object is to provide a spring wound temperature controlled alarm which can be stopped after set in operation only by the actuating spring of the alarm becoming unwound or run down.

A further object is to provide a spring wound temperature controlled alarm which will include a novel and improved construction and arrangement for indicating when the alarm is set for operation and is run down.

A further object is to provide a temperature controlled alarm which will include a sound producing device or siren, a spring motor operatively connected to said sound producing device or siren to cause it to be actuated, novel and improved mechanism for normally retaining said spring motor stationary and said sound producing device or siren inoperative, and a thermostatic element independent of said mechanism, motor and sound producing device or siren for causing the mechanism to release the motor and sound producing device or siren.

A further object is to provide a spring wound temperature controlled alarm which will include a novel and improved construction and arrangement for causing said alarm to be set for operation or re-set after an actuation of the alarm.

A further object is to provide a temperature controlled alarm which will include a sound producing device or siren, a spring motor operatively connected to said sound producing device or siren to cause it to be actuated, mechanism for normally retaining said spring motor stationary and said sound producing device or siren inoperative, a thermostatic element for causing the mechanism to release the motor and sound producing device or siren, and a construction and arrangement independent of said thermostatic element for causing said alarm to be set for operation or re-set after an actuation of the alarm.

And a further object is to provide a spring wound temperature controlled alarm which will include a novel and improved construction and arrangement for causing a sound producing device or siren in proximate relation to the alarm

to be actuated and a signal in remote relation to said alarm to be simultaneously made discernible.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as they remain within the spirit of the invention and the scope of the claims which follow.

In the accompanying drawings forming a part of this specification,

Fig. 1 is a front elevational view of a temperature controlled alarm made according to the invention;

Fig. 2 is a vertical sectional view, taken on line 2—2 in Fig. 1;

Fig. 3 is an enlarged rear elevational view of the disclosure of Fig. 1 with the rearward wall 25 of the frame or cabinet removed;

Fig. 4 is an enlarged fragmentary top plan view of the disclosure of Fig. 1 with the upper wall of the frame or cabinet removed;

Fig. 5 is an enlarged fragmentary horizontal 30 sectional view of the alarm;

Fig. 6 is a detail sectional view, taken on line 6—6 in Fig. 5; and

Fig. 7 is a diagrammatic view of a construction and arrangement for making a signal in remote relation to the temperature controlled alarm discernible simultaneously with actuation of said alarm.

With respect to the drawings and the numerals of reference thereon, a frame or cabinet 40 of the temperature controlled alarm is of rectilinear configuration and includes an upper wall 11, a lower wall 12, a front wall 13, a rear wall 14, side or end walls 15 and 16, and a horizontal partition wall 17 dividing the frame or cabinet into an upper compartment 18 and a lower compartment 19.

A spring motor 20, and speed increasing gearing, denoted generally at 21, are situated within the lower compartment 19 and are suitably 50 and conveniently mounted upon the rear wall 14 and the front wall 13, as well as upon a vertical plate 22 situated between and in parallel, spaced relation to said rear and front walls and fixed, as at 23, upon said lower wall 12.

More explicitly, the spring motor 20 includes a

shell 24 rotatably mounted upon a horizontal shaft 25 having its opposite end portions rotatably mounted in the rear wall 14 and the vertical plate 22, respectively, and a coil or clock spring 26 within the shell 24 having its inner end secured, as at 27, to said horizontal shaft 25 and its outer end secured, as at 28, to the inner surface of a circumferential portion of said shell.

A winding stem 29 for the spring motor 20 is rotatably mounted in the end or side wall 15, and a ratchet wheel 30 fixed to said winding stem is adapted to be releasably engaged by a pawl 31 pivoted upon the inner surface of said end or side wall 15 to permit turning movement of the winding stem to cause the spring motor to be energized and to preclude turning movement of said winding stem in opposite direction. A leaf spring 32 back of said pawl resiliently retains the pawl in engagement with the ratchet wheel 30. A bevel gear 33 fixed on the winding stem 29 is in mesh with a bevel gear 34 fixed on a stub shaft 35 mounted in the rear wall 14, and a gear wheel 36 fixed on said stub shaft is in mesh with a gear wheel 37 rotatably mounted on the horizontal shaft 25 and rigid with the shell 24. Assuming said horizontal shaft 25 to be held stationary, it is apparent that the spring motor 20 can be energized in response to turning movement of the winding stem 29 and retained in energized condition by engagement of the pawl 31 with the ratchet wheel 30.

The speed increasing gearing 21 includes a relatively large gear wheel 38 situated adjacent the vertical plate 22 and fixed on the horizontal shaft 25, and a driving shaft 39, rotatably mounted on the vertical plate 22 and the front wall 13, for a sound producing device or siren 40 is adapted to be driven at high speed by the spring motor through the instrumentality of said gear wheel 38, a smaller gear wheel 41 fixed on a second horizontal shaft 42 rotatably mounted in said vertical plate and front wall, a larger gear wheel 43 fixed on said shaft 42, a smaller gear wheel 44 fixed on a third horizontal shaft 45 rotatably mounted in said vertical plate and front wall, a larger gear wheel 46 fixed on said shaft 45, and a smaller gear wheel 47 fixed on the driving shaft 39. The sound producing device or siren 40 is rigidly supported, as at 48, upon the outer surface of the front wall 13 of the frame or cabinet 10. The construction and arrangement are such that rotation of the driving shaft 39 will cause the device or siren 40 to produce sound or noise.

The speed increasing gearing 21 is adapted to be fastened or locked against turning movement, when this is intentional, to retain the sound producing device or siren inactive against tendency of the spring motor when energized toward actuating said device or siren, and to be released for turning movement, when this is intentional, to permit said sound producing device or siren to be actuated by said spring motor. Mechanism for fastening or locking and releasing said gearing 21 is, in the main, situated within the upper compartment 18 of the frame or cabinet.

A vertical lever 49, pivotally mounted, as at 50, upon an ear or ears supported by the horizontal partition wall 17, includes a lower, shorter arm 51 of said lever in the lower compartment 19 extending obliquely downwardly from the wall 17 in direction substantially tangentially of the gear wheel 46, and an upper, longer arm of the lever extending upwardly through an elongated slot 52 in said wall 17.

The lower end of the lower, shorter arm 51 of 75

the vertical lever 49 includes an integral hook 53 which as shown is substantially perpendicular to said lower, shorter arm and is disposed substantially radially of the gear wheel 46. Said integral hook is adapted to be selectively engaged between gear teeth 54 upon said gear wheel 46 to lock or fasten the gearing 21 against movement and to be released from engaging position between gear teeth 54. The construction and arrangement are such that when the integral hook 53 is engaged between gear teeth 54, tendency toward rotation of the gear wheel 46 is overcome by the lower, shorter arm 51 acting along a line which extends tangentially of said gear wheel and through the pivotal support 50. Thus, the teeth 54 of the gear wheel 46 will exert no appreciable force tending to cause said integral hook to become removed from engagement with said gear wheel, and tendency toward turning movement of the gearing 21 will be resisted directly by said pivotal support 50.

The upper, longer arm of the vertical lever 49 extends upwardly in the upper compartment 18 and is of general V-shape. A lower portion 55 of the upper, longer arm, adjacent the pivotal support 50, is disposed obliquely to the horizontal partition wall 17 and in substantially right-angle relation to the lower, shorter arm 51, and an upper portion 56 of said upper, longer arm is disposed directly above said lower portion 55. The lower portion 55 and the upper portion 56 of the upper, longer arm of the vertical lever 49 may be of substantially equal length, and said lower and upper portions 55 and 56 meet at a location 35 57 disposed intermediate the top wall 11 and the partition wall 17. The upper end of the longer arm 56 rigidly supports a lug 58.

A resilient element 59, engaged by the lug 58, has potential to cause the upper, longer arm of 40 the vertical lever 49 to be swung in direction, toward the right in Fig. 3, to cause the integral hook 53 upon the lower, shorter arm 51 of said vertical lever to become removed from between teeth 54 of the gear wheel 46. In the illustrated embodiment of the invention, the resilient element 59 is an electrical conducting member and is insulatively supported, as at 60, upon the inner surface of the front wall 13 of the frame or cabinet 10. The lug 58 will desirably be composed of insulating material.

A second vertical lever 61, for retaining the integral hook 53 upon the lower, shorter arm 51 of the vertical lever 49 engaged between teeth 54 of the gear wheel 46 against tendency of the resilient element 59 toward causing said integral hook to become removed from said gear wheel, is pivotally mounted, as at 62, upon ears supported by the horizontal partition wall 17. Said second vertical lever 61 includes a lower, shorter arm 63 of said lever in the lower compartment 19 extending substantially perpendicularly downwardly through the elongated slot 52, and an upper, longer arm of the lever extending upwardly in the upper compartment 18.

The lower end portion of the lower, shorter arm 63 of the vertical lever 61 is rounded or curvilinear, as at 64, and the rounded or curvilinear portion 64 is adapted to be constantly engaged against the surface of the lower end portion of the lower, shorter arm 51 of the vertical lever 49 which is opposite the integral hook 53, as will be clear from Fig. 3.

The upper longer arm of the vertical lever 61 extends upwardly in the upper compartment 18. A lower portion 65 of said upper longer arm, ad-

adjacent the pivotal support 62, is disposed in alignment with the lower, shorter arm 63, and an upper portion 66 of said upper, longer arm of the second vertical lever is disposed in oblique angle relation to the lower portion 65 and extends away from the side of said lower portion 65 which is opposite the vertical lever 49. Said vertical lever 49, the second vertical lever 61 and the gear wheel 46 are situated in a single vertical plane disposed longitudinally of the frame or cabinet 10 in the disclosure as made.

A latch, denoted generally at 67, for retaining the lower, shorter arm 63 of the vertical lever 61 engaged against the lower, shorter arm 51 of the vertical lever 49 to hold the integral hook 53 engaged between teeth 54 of the gear wheel 46, is situated in the upper compartment 18, at the side of the vertical lever 61 opposite the vertical lever 49, is disposed perpendicularly of the plane of the gear wheel 46, and is mounted for horizontal sliding movement in direction transversely of the frame or cabinet. More explicitly, said latch 67 is slidably supported by a bracket arm 68 fixed, as at 69, upon the upper surface of the partition wall 17. Said bracket arm includes vertically spaced, upper and lower annular clamp elements 70 thereof, and the clamp elements 70 rigidly support parallel tubular guides 71, including a tubular guide 71 in each clamp element, disposed in perpendicular relation to the front wall 13. A U-member 72 includes a base 13 thereof adjacent the ends of the tubular guides 71 opposite the upper portion 66 of the vertical lever 61, an upper, shorter leg 74 thereof slidably mounted in the upper tubular guide 71 and a lower, longer leg 75 thereof slidably mounted in the lower tubular guide 71. The free end portion 76 of the upper, shorter leg 74 extends a relatively short distance beyond the end of the corresponding tubular guide opposite the base 73, and the upper portion 66 of the vertical lever 61 is adapted to be swung downwardly and disposed beneath said free end portion 76 to thus cause the integral hook 53 to be held between teeth 54 of the gear wheel 46, as these mentioned parts are disclosed in Fig. 2 and in full lines in Fig. 3. Spaced apart, vertical posts 77 secured to and extending downwardly from the upper wall 11 of the frame or cabinet 10 constitute means for guiding said longer portion 66 for vertical swinging movement. The free end portion 78 of the lower, longer leg 75 extends a comparatively long distance beyond the end of the corresponding tubular guide opposite said base 73. As shown more clearly in Figs. 2 and 4, said free end portion 78 passes freely through an opening 79 in the front wall 13 and terminates within a vertical chamber 80 defined by a, desirably screen covered, housing 81 suitably and conveniently secured upon the frame or cabinet. An upwardly extending actuating pin 82 rigid with the lower, longer leg 75 and situated adjacent the free end of the upper, shorter leg 74, below and outwardly of said upper, shorter leg, is for a purpose to be set forth. A leaf spring 83 secured upon the end or side wall 15 and in engagement with the base 73 of the U-member 72 resiliently urges the upper and lower legs of said U-member in direction away from said leaf spring and toward the front wall 13.

A thermostatic element or bimetallic blade 84 is for causing the free end portion 76 of the upper, shorter arm 74 of the U-member 72 to become removed from its latching position above the upper portion 66 of the vertical lever 61, and

said element or blade 84 is of type to become warped or bent in response to temperature changes. More explicitly, a lower portion of the element or blade 84 is adjustably mounted, as at 85, in a lower portion of the vertical chamber 80, and an upper portion of said element or blade is situated in an upper portion of said vertical chamber at the outer side of and adjacent the free end portion 78 of the longer, lower leg 75 of the U-member 72. The construction and arrangement are such that when the thermostatic element or bimetallic blade 84 is warped or bent in direction toward said U-member 72, as in response to the elevation of the temperature of atmospheric air, said element or blade will engage the free end of the lower, longer leg 75 and cause the U-member to be slid inwardly, so that continued inward movement of said U-member will cause the free end portion 20 76 of the upper, shorter leg 74 to be removed or withdrawn from position above the upper portion 66 of the lever 61. The element or blade 84 will of course push the U-member 72 inwardly against the weaker resilient action of the leaf spring 83.

It will be evident that when the longer arm 66 is set beneath the free end portion 76, as disclosed in Figs. 2 and 4, and in full lines in Fig. 3, the integral hook 53 will be situated between teeth 54 of the gear wheel 46 by the lower, shorter arm 63 of the vertical lever 61 to thus retain said gear wheel, the gearing 21, the spring motor 20 and the siren 40 inactive. See the full line position of the lower, shorter arms 51 and 63 in Fig. 3. When, however, the thermostatic element or blade 84 is warped or bent to cause said free end portion 76 to be removed or withdrawn, the resilient element 59 will act to release said integral hook from engagement with said gear wheel 46. See the dotted line positions of said arms 51 and 63 in said Fig. 3. Obviously, the alarm will become operative upon withdrawal of the integral hook 53 from the gear wheel 46, and actuation of said alarm cannot be stopped until the coil or clock spring 26 of the spring motor 20 has become spent. That is, it is practically impossible to cause the integral hook 53 to become engaged between teeth 54 of the gear wheel 46 while said gear wheel is rapidly rotating.

A construction and arrangement for setting and re-setting the alarm is very plainly disclosed in Figs. 1 to 4 of the drawings.

A horizontal guide rod 86 is disposed in the upper compartment 18 in slightly spaced, parallel relation to the front wall 13, and opposite ends of said guide rod 86 are rigidly supported, as at 87, upon the end or side walls 15 and 16.

An actuating knob 88 is situated at the outer side of the front wall 13 of the frame or cabinet and is slidably mounted in an elongated slot 89 through said front wall. A vertical member 90 rigid with an inner portion of said knob 88 includes a forked portion 91 adapted for sliding movement along the guide rod 86. A tension coil spring 92 upon said guide rod 86 has one of its ends secured, as at 93, at or adjacent to the side wall 16, and its other end secured, as at 94, to a carriage 95 adapted for sliding movement along the guide rod 86. The forked portion 91 is situated between and engaged by coils of the spring 92, and the construction and arrangement are such that the part 96 of said coil spring 92, between the wall 16 and said forked portion 91, is under sufficient tension to normally re-

tain the knob 88 at the end of the elongated slot 89 adjacent the wall 16 and the forked portion 91 at its farthest distance from the U-member 72. The part 97 of the coil spring 92, between said forked portion 91 and the slideable carriage 95, acts as a compression spring in the performance of its intended function. A stud 98 rigid with the carriage 95 extends inwardly from said carriage and is engaged against the concave side of the location 57 where the lower and upper portions 55 and 56 of the upper, longer arm of the vertical lever 49 meet. The construction and arrangement are such that said part 97 of said coil spring 92 is under slight compression between the carriage 95 and the upper, longer arm of the vertical lever 49, but under insufficient compression to maintain the integral hook 53 engaged between teeth 54 of the gear wheel 46 against the stronger action of the resilient element 59 when the vertical lever 61 is released from the latch 67.

A second coil spring 99 is slidably situated upon the guide rod 86 at the side of the carriage 95 opposite the coil spring 92 and between said carriage 95 and a second carriage 100. The second coil spring 99 desirably has less strength than the part 97 of the coil spring 92 and is normally under neither tension nor compression. Said coil spring 99 has its opposite ends secured, as at 101 and 102 to the carriages 95 and 100, respectively.

A horizontal actuating rod 103, rigid with the vertical member 90 and guided at its end portion opposite said member by an eye 104 upon the front wall 13 of the frame or cabinet 10, is disposed in slightly spaced, parallel relation to said front wall at elevation somewhat above the guide rod 86. A stud 105, rigidly supported by the actuating rod 103 at location between the carriages 95 and 100 and adjacent said carriage 100, extends downwardly to position where it will become engaged against the adjacent surface of the carriage 100 when the setting and re-setting mechanism is operated. Said carriage 100 includes a vertical bevel surface 106 at its side adjacent the U-member 72 adapted to become engaged against the upwardly extending actuating pin 82 when said setting and re-setting mechanism is operated.

The integral hook 53 is moved from its dotted line position to its full line position in Fig. 3 by manual actuation of the knob 88 toward the left. Such actuation of said knob causes the part 97 of the coil spring 92 to be under compression sufficiently great to move the upper, longer portion of the vertical lever 49 toward the left in said Fig. 3 against the weaker opposed action of the resilient element 59. The weight of the upper portion 66 of the vertical lever 61 is sufficient to cause said upper portion to move downwardly by gravity when the lower, shorter arm 63 of said lever 61 is allowed to swing toward the right in Fig. 3 by movement of the lower, shorter arm 51 in direction away from said lower, shorter arm 63 and against the gear wheel 46. Continued actuation of the knob 88 in direction which causes the integral hook 53 to engage between gear teeth 54 of the gear wheel 46 causes the stud 105 to engage the carriage 100 and move said carriage against the resilient action of the coil spring 99, toward the U-member 72. In turn, the bevel surface 106 causes the pin 82 and the U-member 72 to be moved inwardly and the free end portion 76 to be withdrawn from beneath the upper portion 66 so that said portion 66 will

travel by gravity to elevation just below said free end portion 76. Upon release of the knob 88 the several entities of the setting and re-setting mechanism will return to their normal positions, and the construction and arrangement are such that upon return of the knob 88 and associated parts to normal position, the carriage 100 releases the U-member 72 to the resilient action of the leaf spring 83 before the stud 98 upon the carriage 95 releases the vertical lever 49 to the action of the resilient element 59. That is to say, as the entities of the setting and re-setting mechanism are returning to normal positions, the free end portion 76 of the U-member 72 becomes positioned over and across the upper surface of the portion 66 of the vertical lever 61 while the part 97 of the coil spring 92 is yet under sufficient tension to be stronger than the resilient element 59.

Of course, the spring motor 20 will be wound up, in the manner as before set forth, while the gearing 21 is held stationary by engagement of the integral hook 53 between teeth 54 of the gear wheel 46.

An L-shape element 107, secured to the upper end of the vertical lever 49, is for the purpose of indicating whether or not the alarm is set for operation. The outer end portion of said element 107 is arranged in an arcuate slot 108 in the front wall 13 of the frame or cabinet 10 and includes a finger 109 at the outer side of the frame or cabinet adjacent said slot. In the disclosure as made, said finger will be at an upper portion of the arcuate slot when the alarm is set and at a lower portion of said slot when the alarm not set, and, consequently, run down.

The resilient element or conducting member 59 is included in an electrical circuit also including a second conducting member 110 insulatively supported, as at 111, upon the front wall 13 of the frame or cabinet 10 in adjacent relation to said element or member 59. The electrical circuit having the conducting members 59 and 110 additionally includes an instrument 112, which as disclosed is an electric lamp, adapted to be energized to produce a discernible signal. A battery for energizing the instrument or electric lamp 112 is indicated at 113. A lead wire 114 extends from said battery to the instrument or lamp 112, a lead wire 115 extends from said instrument or lamp to the conducting member 59, and a lead wire 116 extends from the conducting member 110 to the battery.

The construction and arrangement are such that when the integral hook 53 is maintained between teeth 54 of the gear wheel 46, the lug 58 upon the upper end of the vertical lever 49 retains the resilient conducting member 59 out of engagement with the conducting member 110, as in Fig. 3, and when the lower, shorter arm 51 of said lever 49 is released by the vertical lever 61 said resilient conducting member 59 not only acts to remove or withdraw said integral hook 53 from the gear wheel 46 but also engages itself against the conducting member 110 to thus close the circuit including the instrument or lamp 112. In short, the conducting members 59 and 110 constitute a switch adapted to be closed simultaneously with setting-off the sound producing device or siren 40 to cause a signal in remote relation the alarm to be made discernible.

What is claimed is:

1. In a temperature controlled alarm, a spring motor, a sound producing device, gearing operatively connecting said spring motor with said

sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, a resilient element having potential tending to remove said first pivoted lever from engagement with said gearing, a latch element for retaining said second pivoted lever against said first pivoted lever to retain the latter engaged with said gearing in opposition to potential exerted by said resilient element, and a thermostatic element for actuating said latch element to release said second pivoted lever to thus permit said resilient element to remove said first pivoted lever from said gearing.

2. The combination as specified in claim 1, and means for re-setting said latch element after an actuation of said alarm to retain said second pivoted lever engaged against said first pivoted lever and the first pivoted lever engaged with said gearing.

3. In a temperature controlled alarm, a spring motor, a sound producing device, gearing operatively connecting said spring motor with said sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, a resilient element having potential tending to remove said first pivoted lever from engagement with said gearing, a slideable latch element for retaining said second pivoted lever against said first pivoted lever to retain the latter engaged with said gearing in opposition to potential exerted by said resilient element, and a thermostatic element for slidably actuating said latch element to release said second pivoted lever to thus permit said resilient element to remove said first pivoted lever from said gearing.

4. The combination as specified in claim 3, and means assisted by gravity for slidably re-setting said latch element after an actuation of said alarm to retain said second pivoted lever engaged against said first pivoted lever and the first pivoted lever engaged with said gearing.

5. In a temperature controlled alarm, a spring motor, a sound producing device, gearing operatively connecting said spring motor with said sound producing device, mechanism including a pivoted lever adapted to be engaged with said gearing to fasten the gearing in stationary position to thus render said spring motor inoperative and said sound producing device inactive, a resilient conducting member, a conducting member adjacent said resilient conducting member, said resilient conducting member having potential tending to remove said pivoted lever from engagement with said gearing and tending to cause the resilient conducting member to become engaged with said conducting member, means for causing said resilient conducting member to remove said pivoted lever from said gearing and to itself engage said connecting member, an electrical circuit adapted to be made by engagement of said resilient conducting member with said conducting member, and an instrument in said electrical circuit adapted to be energized to produce a discernible signal.

6. In a temperature controlled alarm, a spring

motor, a sound producing device, gearing operatively connecting said spring motor with said sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, a resilient element having potential tending to remove said first pivoted lever from engagement with said gearing, a latch element for retaining said second pivoted lever against said first pivoted lever to retain the latter engaged with said gearing in opposition to potential exerted by said resilient element, and a temperature responsive element for accomplishing longitudinal actuation of said latch element to cause said second pivoted lever to be released from said latch element and to permit said resilient element to remove said first pivoted lever from said gearing.

7. The combination as specified in claim 6, and means for actuating said first pivoted lever against the potential of said resilient element into engagement with said gearing thus to permit said latch element to be re-set after an actuation of said alarm to retain said second pivoted lever engaged against said first pivoted lever and the first pivoted lever engaged with said gearing.

8. The combination as specified in claim 3, and means for actuating said first pivoted lever against the potential of said resilient element into engagement with said gearing thus to cause said second pivoted lever to be situated by gravity at position permitting said latch element to be re-set after actuation of said alarm to retain the second pivoted lever engaged against said first pivoted lever and the first pivoted lever engaged with said gearing.

9. The combination as specified in claim 3, and an entity actuatable by said mechanism for indicating the position of said first pivoted lever.

10. In a temperature controlled alarm, a spring motor, a sound producing device, gearing operatively connecting said spring motor with said sound producing device, mechanism including a pivoted lever adapted to be engaged with said gearing to fasten the gearing in stationary position to thus render said spring motor inoperative and said sound producing device inactive, a resilient conducting member, and a conducting member adjacent said resilient conducting member, said conducting members together constituting a switch, and said resilient conducting member having potential tending to remove said pivoted lever from engagement with said gearing and tending to cause the resilient conducting member to become engaged with said conducting member.

11. In a temperature controlled alarm, a spring motor, a sound producing device, gearing operatively connecting said spring motor with said sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, a resilient element having potential tending to remove said first pivoted lever from engagement with said gearing, a latch element for retaining said second pivoted lever against said first pivoted lever to retain the latter engaged with said gearing in opposition to

potential exerted by said resilient element, a thermostatic element for actuating said latch element to release said second pivoted lever to thus permit said resilient element to remove said first pivoted lever from said gearing, and an entity actuated by said mechanism for indicating the position of one of said pivoted levers.

12. The combination as specified in claim 1, and means assisted by gravity for re-setting said latch element.

13. In a temperature controlled alarm, a spring motor, a sound producing device, gearing operatively connecting said spring motor with said sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, a resilient element having potential tending to remove said first pivoted lever from engagement with said gearing, a latch element for retaining said second pivoted lever against said first pivoted lever to retain the latter engaged with said gearing in opposition to potential exerted by said resilient element, a temperature responsive element for accomplishing longitudinal actuation of said latch element to cause said second pivoted lever to be released from said latch element and to permit said resilient element to remove said first pivoted lever from said gearing, and means for actuating one of said pivoted levers thus to permit said latch element to be re-set.

14. The combination as specified in claim 6, and means for re-setting said latch element.

15. In a temperature controlled alarm, a

spring motor, a sound producing device, gearing operatively connecting said spring motor with said sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, a resilient element having potential tending to remove said first pivoted lever from engagement with said gearing, a latch element for retaining said second pivoted lever against said first pivoted lever to retain the latter engaged with said gearing in opposition to potential exerted by said resilient element, and a thermostatic element for actuating said latch element to cause said mechanism to release said gearing.

16. In a temperature controlled alarm, a spring motor, a sound producing device, gearing operatively connecting said spring motor with said sound producing device, mechanism including a first pivoted lever adapted to be engaged with said gearing to fasten the gearing in stationary position to thus render said spring motor inoperative and said sound producing device inactive and a second pivoted lever engaged with said first pivoted lever, means for removing said first pivoted lever from engagement with said gearing, a latch element for retaining said second pivoted lever against said first pivoted lever and the latter against said gearing, and a temperature responsive element for actuating said latch element to cause said means to release said gearing.
